[57] CLAIM

The ornamental design for a storage battery cart, as shown and described.

DESCRIPTION

FIG. 1 is a front perspective view of a storage battery cart showing my new design;

FIG. 2 is a rear elevational view thereof;

FIG. 3 is a top plan view thereof;

FIG. 4 is a fragmentary front elevational view thereof;
FIG. 5 is a fragmentary side elevational view thereof,
the opposite side elevational view being a mirror image
of that shown; and

FIG. 6 is a fragmentary bottom plan view thereof.
The broken lines shown in FIGS. 1, 2, 4 and 5 are for
illustrative purposes only and form no part of the
claimed design. A portion of the handle in FIGS. 4, 5
and 6 is shown broken away for convenience of illustration.
